TELEPHONE SYSTEM.

1,303,937.

Specification of Letters Patent. Patented May 20, 1919.

Application filed November 25, 1914, Serial No. 874,003. Renewed August 1, 1918. Serial No. 247,868.

To all whom it may concern:

Be it known that I, TALBOT G. MARTIN, a citizen of the United States of America, and resident of Chicago, Cook county, Illinois, have invented certain new and useful Improvements in Telephone Systems, of which the following is a specification.

My invention relates to automatic and semi-automatic telephone systems. More particularly my invention relates to telephone systems in which a plurality of trunks are made common for the purpose of extending connections from one point to another. Among the objects of my invention are the following: to provide means for preventing two subscribers calling in onto an auxiliary line, such as an operator's head-set at the same time; to provide means for making all of the trunks running to a particular point, such as to a particular operator, busy when a connection is extended to said operator, so as to permit only one call to go to such an operator at the same time, and to provide means for accomplishing this result over a busy trunk circuit; to provide means whereby when a subscriber takes a trunk the means for connecting the other trunks with an auxiliary circuit, such as an operator, will be rendered inoperative; to provide means for preventing interference with release circuits involving busy trunks; to provide means for disconnecting a trunk from the auxiliary circuits when a connection is extended from the trunk; to provide means for restoring the connecting means of idle trunks to normal condition when a connection is extended from a seized trunk and disconnected from the auxiliary circuit; to provide a special form of busy test signaling apparatus which will automatically indicate to the operator whether a call is a reverting call or otherwise; to provide an improved form of ringing circuit; to provide a special arrangement for indicating to the calling subscriber whenever ringing current is being transmitted to the talking circuit, and to provide a special meter circuit, the operating impulse of which is controlled by quick and slow relays.

It is also the object of my invention to provide certain details and features of improvement and combinations tending to increase the efficiency and serviceability of a telephone system of the above character.

The means to accomplish the foregoing and other useful ends are hereinafter set forth and claimed.

In the accompanying drawing a complete circuit connection is shown between a calling subscriber A and a called subscriber A' embodying the principles of my invention. The connection is completed through the medium of the subscriber's individual switch C, cord circuit E and the called subscriber's individual switch C' to the called sub-sta-
tion A'.

The line conductors 10 and 11 of the subscribers' substation A terminate in the individual or line switch C. The line switch shown at C is one of a group of similar line switches the plungers (not shown) of which engage a shaft and are controlled by the operation of the master switch shown at D in such a manner that they are, when in normal position, held directly in front of the terminals of a trunk line leading to an idle cord circuit E. The cord circuit E is equipped with the necessary apparatus for completing connection with any one of a plurality of substations (only one of which is shown) connected to the line conductors 10' and 11' through the line switch C'. Although there is shown only one substation A' connected to the line conductors 10' and 11' it will be understood that a plurality of like substations may be connected to the said conductors. The ringers of the different substations may be arranged in any well known manner to respond to the ringing current generated by some particular one of a plurality of generators.

The subscribers' substations A and A' are of any suitable or approved type and comprise the usual receivers 2 and 2', transmitters 3 and 3', ringers 4 and 4', condensers 5 and 5' and switch hook springs 7, 8, 9 and 7', 8', 9'. They are connected to the exchange by the conductors 10, 11, and 10', 11', respectively, where they terminate in individual switches C and C' respectively, from which normal conductors extend to a plurality of jacks; only one of which is shown for each line, as J and J', respectively.

The primary switch C is of the general type of line switch shown in British patent to R. W. James, No. 26,301 of 1906, the particular form shown, however, being, similar to that shown in British patent to T. G.

Martin, No. 1419 of 1910, with the exception that the line relay and operating magnets are made separate instead of being combined in a single structure. Among other details, 5 the line switch comprises a plunger (not shown) carried upon the end of the plunger arm 12 which is adapted, when the plunger arm is attracted by the magnet 13, to force the plunger into a bank of contact springs, 10 forcing the springs 17, 18, 19 and 20 into engagement with the springs 21, 22, 23 and 24 respectively. The magnet 13 also controls the cut-off armature 16, and comprises two windings, namely, the pull-in winding 14 and the cut-off or holding winding 15. The winding 14 is strong enough to operate both the plunger arm 12 and the cut-off armature 16, while the winding 15 is only strong enough to operate the cut-off armature 16 and to hold the plunger arm 12 in an operated position after it has once been drawn down by the winding 14. The line relay 25 is slow acting, that is, slow to de-energize after its energizing circuit has 20 been broken, so that it may keep the operating winding 14 energized for a short time after the cut-off armature 16 has operated to disconnect said line relay 25 from the line. Although only one set of springs 17-24 25 inclusive is shown, each line is provided with a plurality of such sets, each set forming the terminal of a trunk line leading to the cord circuit E. Each trunk line is connected in multiple with the corresponding 30 springs of all the switches of the group which is controlled by the master switch D. The switch C is controlled by the subscriber through the medium of the line relay 25, as will be hereinafter explained. The plungers 35 of the line switch are preferably of the self alining type, that is, they always return to locking engagement with the master switch shaft when they become idle.

The master switch D is of the same general type as that disclosed in British Patent 45 No. 26,301 of 1910, referred to above, being, however, of the particular type disclosed in French Patent No. 449,234 of 1912, the circuits however, being slightly modified.

50 Among other details, the master switch D comprises a starting relay 26, a locking magnet 27 and a restoring magnet 28. As is shown, the usual plunger guide shaft 29, through the medium of which the master switch controls the plungers, is connected with the rotary shaft 29^a in such a manner that, as said shaft is rotated back and forth, the plunger guide shaft 29 is oscillated about said shaft 29^a as an axis. The shaft 29^a is 55 adapted to be rotated in one direction by a spring (not shown) and to be returned against the tension of said spring by a solenoid 30. Secured to the shaft 29^a is a cam member 31 provided along its outer edge 60 with notches 32, one for each trunk line to

which the line switches have access. The shaft 29^a is normally locked against rotation in either direction by the engagement of the lever 33 with one of the notches 32. The lever 33 is controlled by the armature 70 of the relay 27 in such a manner that when said relay is energized, the lever is withdrawn from the cam 31 so as to unlock the shaft 29^a. The speed of rotation of the shaft 29^a and the plunger arm shaft 29 is 75 regulated by means of a suitable governor 34. The spring 35 of the relay 28 is locked in its operated position by the engagement of the spring 35 with the detent on the side of spring 36. The springs are unlocked by 80 the arm 37 when the shaft 29^a has reached the limit of its travel in one direction. The master switch D is also provided with a bank of contacts *a*, one for each trunk. A wiper 41 keeps the common segment 42 in 85 electrical connection with the individual contact *a* corresponding to the trunk line before which the idle plungers are resting. In general, the operation of the master switch is as follows: Whenever a trunk line is seized 90 by a line switch, the relay 26 is energized which in turn energizes the relay 27 to unlock the shaft 29^a, through the medium of the double arm 33 and cam 31, a spring (not shown) thereupon rotating the shaft 29^a to 95 cause the plunger guide shaft 29 to move the idle plungers away from the trunk just seized and to an idle trunk line. When an idle trunk is reached, the relay 27 deenergizes and again locks the shaft. When the 100 plungers in their operation pass beyond the last trunk line, the arm 38 forces the spring 39 into contact with the spring 40, whereupon the relay 28 energizes and closes the circuit of the solenoid 30. The solenoid, 105 upon energizing rotates the shaft 29^a back to its initial position, so as to bring all the plungers which are in engagement with the plunger shaft back to a position opposite the first trunk line and to restore the 110 tension of the operating spring. When the plunger shaft reaches its initial position, the arm 36 unlocks the spring of relay 28, which permits the solenoid to de-energize and the plunger shaft to come 115 to rest. A relay K is associated with each trunk line leading from the group of line switches to which line C belongs. The relay K is energized whenever its corresponding trunk is in use. When all the trunks 120 leading from the said group become busy at one time, and therefore all the relays K energize, the relays L and M become energized over the following circuit: from ground G¹¹ through the contact of springs 125 92 and 93 of each trunk relay K and through the said relays L and M to battery B. The relay L, upon energizing, removes battery from the pull-in winding of all the line switches of the group, by opening the con- 130

tact springs 55 and 56. The relay M, upon energizing, opens the circuit of the start relay 26 of the master switch D at the springs 61 and 62, so that the said master switch 5 will not operate until a trunk line becomes idle.

The trunk line seized by the switch C terminates in the cord circuit E, through the medium of which the circuit is completed to 10 the called subscriber's line. The two ends of the cord circuit are connected together through the medium of the condensers C' and C''. The cord circuit is also provided with the usual calling and answering super- 15 visory signals t and t^2 and the necessary relays for controlling the same. The relay I is a group busy relay, that is, it is a relay to make all trunks to an operator's position busy as long as there is an unanswered call at said 20 operator's position. The relay I may be common to all the cord circuits of an operator's position. The meter X is the means for registering all calls handled by one operator. The relays Z', Z'' and Z''' furnish means for 25 giving a discriminating busy test whereby the operator can ascertain whether she is testing a multiple jack of the calling line connected to the answering end of the cord or of some other busy line. The keys k' , k'' , 30 k''' , k^4 are the means by which any one of a plurality of generators (only one shown) may be connected to the cord circuit E for signaling purposes. The said keys are so arranged mechanically that when any one of 35 these keys are depressed, any other depressed key will be restored to normal, so as not to allow two generators to be connected to the leads 166 and 167 at the same time. The conductor 200 is multiplied through the contacts of springs 107' and 108' and also 107 and 108 of every cord circuit common to an 40 operator's position, the function of which, is to prevent the connecting of the operator's head set P' to more than one cord circuit at 45 a time, if it so happened that more than one call was successful in reaching an operator's position at one time.

Having given a general description of the apparatus involved in the system, in order to 50 give a complete understanding of my invention it will be described how the subscriber at the substation A may obtain connection with the subscriber at substation A'. When the receiver at the substation A is removed 55 from the switch hook preparatory to making a call, the engagement of the switch hook springs completes a bridge across the line through the receiver and transmitter of the substation. The closure of this bridge 60 across the line establishes an energizing circuit for the line relay 25 of the line switch C. This circuit extends from ground G² through the contact of springs 43 and 44, conductor 11, to and through the substation 65 A, return conductor 10, contact of springs

47 and 46, the relay 25 and the conductor 50 to battery B. The relay 25, upon energizing, operates to close the circuit through winding 14 of the line switch C. This circuit extends from ground G³ through the contact of 70 springs 52 and 53, winding 14, contact of springs 55 and 56, conductor 57, contact of springs 58 and 59 to the battery B. The winding 14, upon energizing, attracts the plunger arm 12 (to which is fastened the 75 plunger not shown) and the cut-off armature 16, whereby the line conductors 10 and 11 are extended through the contact of the line switch bank springs 17-21 and 20-24; the release conductor and trunk-guard conductor are also extended at the same time by 80 contact of bank springs 18-22 and 19-23 respectively to the cord circuit E, and the line relay 25 is disconnected from the line. When the connection is extended to the said 85 cord circuit, the line relay F immediately energizes over the following circuit; from ground G⁶ through the winding 66 of relay F, contact of springs 24 and 20, conductor 10 to and through the substation A, return conductor 11, a contact of springs 17 and 21 and the winding 67 of relay F to battery B.

The relay F, upon energizing closes the circuit of the hold-in winding 15 of the line switch C and the trunk relay K (before the 95 line relay 25 deenergizes.) The circuit for said hold-in winding extends from ground G⁸ through the winding of relay H, contact of springs 74 and 75, contact of springs 22 and 18 and the said winding 15 of line switch 100 C to battery B. A guarding ground potential is also supplied to the bush 176 of the multiple jack J to make the calling line test busy. The closing of bank springs 19 and 23 causes the master switch D to operate in a 105 well known manner to move the plungers of all the line switches opposite an idle trunk line. A further result of the energization of the relay F is to close a circuit through the group busying relay I. This circuit extends from ground G⁷ through the contact of springs 69 and 70, contact of springs 84 and 85 and the relay I to battery B. The relay I, upon energizing, closes a circuit through its springs 87, 88, etc., thus placing 115 a guarding potential upon every idle trunk line leading to the operator's position. The circuit for a particular trunk line is as follows: from ground G⁹ through contact of springs 87, contact of springs 83 and 82, contact of springs 76 and 75, conductor 79, conductor 89 and relay K to battery B.

The relay K upon energization, closes a circuit which provides a guarding ground potential at the master switch bank to prevent the master switch from stopping on this particular trunk line. This circuit extends from ground G¹⁰ through the contact of springs 90 and 91 and to master switch bank contact 60. Should the master-switch 125 130

wiper 41 be rotated over its bank to the contact 60 a circuit would then be closed which extends from master switch bank contact 60, through master-switch wiper 41, bank 42, 5 contacts of springs 61 and 62 and relay 26 to battery B. As hereinbefore explained the master switch would then be operated, which in turn would move the plungers away from this trunk line so that it could not be selected. 10 ed. In a like manner a guarding ground potential is supplied from ground G⁹ through the contacts of springs 88, 88^a etc., upon every trunk line leading to this operator's position. The relay H, upon energizing, 15 closes a circuit through the slow acting relay N. This circuit extends from ground G¹² through the contact of springs 103 and 104, springs 95 and 94 and the relay N to battery B. The relay N, upon energizing, 20 closes a circuit through the line signal lamp t and the relay O. The circuit for the line signal lamp extends from ground G¹³ through the springs 107—109 and 107'—109' in parallel, springs 71 and 72 and the said 25 lamp to battery B. The circuit for the relay O extends from ground G¹³ through the springs 109—107 and 109'—107' in parallel and the said relay O to battery B. The relay O upon energizing connects the operator's 30 head set across the line-conductors of cord circuit E. A further result of the energization of relay N is to disconnect ground from the conductor 200 which multiples through all the other cord circuits of the 35 operator's position, thus making it impossible for the line signal lamp t or the relay O (which connects the operator's head set to the cord circuit) of any other cord circuit in a certain position to operate.

40 The disconnection of ground (caused by the energization of relay N) from the conductor 200 which multiples through all cords of one operator's position, prevents more than one sub-station from connecting with the operator's head set. This is accomplished in the following manner: relay N, upon energizing, remains in that condition until the operator plugs into a jack to complete the call as will be hereinafter explained. 45 It is therefore obvious that there is no ground on springs 108 and 108' which lead to the conductor 200; conductor 200 multiples to corresponding springs 107 and 107' in the remaining cord circuits associated with the operator's position. It is therefore evident that when a call is directed over any other cord circuit it can proceed as far as and energize its relay N. However there being no ground on the corresponding springs 107 and 107' associated with its cord circuit therefore, when the corresponding springs 107, 109 and 107' and 109' are in contact there is no ground supplied to energize the relay O. The relay O must be energized to complete a connection through

50

55

60

to the operator's head set. Therefore it is evident that only one substation can be in connection with the operator's head set at one time.

The operator, upon noticing the line signal lamp glowing, inquires of the calling subscriber the subscriber desired. We will assume that it is the subscriber at substation A', whose bells are so arranged as to respond to the ringing current from the generator R'. The operator now touches the tip of plug P to the bush of jack J', if the line is busy, the relay Z' will immediately energize and close the contact of springs 172 and 173, thus giving the operator a click in the ear. 70 The energizing circuit for relay Z' extends from ground upon the bush of jack J' through the tip of plug P, springs 160 and 161, springs 100 of relay Q, springs 97 and 96 of relay H, relay Z' and the coil Z² to 75 battery B. The circuit which is closed to produce the busy click in the operator's receiver may be traced from ground G¹⁹ through relay Z³ contacts of springs 172 and 173 of relay Z', operator's receiver 119, 80 winding 120 of induction coil, springs 117 and 118 of relay O, and lower winding 170 of relay Y to battery B. The operator immediately informs the calling subscriber that the line is busy or plugs the plug P into a 85 special busy tone jack similar to that shown in the patent to W. W. Dean, No. 853,682, issued May 14, 1907, giving the calling subscriber a busy signal. If the substation desired is a substation upon the calling subscriber's line, when the operator touches the plug P to the jack J', the relay Z' will act as a buzzer, due to the fact that the said relay short circuits itself at the springs 174 and 175 every time the said relay energizes. 90 The short circuiting path for relay Z' extends from the bush of jack J (or one of its multiples) through the bank springs 18 and 22, springs 115 and 116, springs 175 and 174, relay Z', springs 96 and 97, springs 100, 95 springs 161 and 160 and the tip of plug P to the bush of jack J. The buzzing effect of the relay Z' notifies the operator that the substation desired is one upon the calling substation's line and she will immediately 100 proceed to complete the connection.

Assuming that the line desired is idle, the operator immediately plugs the plug P into the jack J' which causes the relay Q to immediately energize. This circuit extends 105 from ground G¹⁵, through the said relay, sleeve of plug P bush of jack J', cut-off winding 123 of line switch C' to battery B. The cut-off winding upon energizing, disconnects the line relay 140 from the line and 110 completes the connection through to the substation A'. The relay Q, upon energizing, breaks the circuit of relay N at the springs 104 and 103 and closes a circuit through the relay W and the supervisory lamp t² at the 115

120

125

130

springs 103 and 102. A further result of the energization of relay Q is to disconnect the relays Z' and Z² from the tip strand of the cord circuit E at the springs 100, and 5 to connect a holding ground to the trunk release conductor 79 through the springs 98 and 99 independent of the springs 74 and 75. The circuit for this additional holding ground extends from ground G⁸ through 10 winding of relay H, springs 98 and 99 to release trunk conductor 79. The relay W upon energizing, opens the circuit of the group busying relay I at the springs 85 and 84 and closes the circuit through the meter 15 control magnet X at the springs 80 and 81. The circuit of said meter control magnet being opened, an instant later, at the springs 106 and 105 when the slow-acting relay N deenergizes. The relay N, upon deenergizing, opens the circuit of the relay O 20 and lamp t at the springs 107, 109 and 107'-109' in multiple. The relay O, upon deenergizing, disconnects the operator's head set from the cord circuit E. The operator's 25 position is now in readiness to receive another call.

The operator now presses the key k' to connect the generator R' to the called line. The key k' locks in its depressed position 30 (holding the contact of springs 146-147 and 142-143 closed but allowing the springs 144 and 145 to make contact for an instant and then to separate) and restores the key previously operated to normal. The relay 35 S is energized as soon as key k' is depressed and operates to close a locking circuit through the springs 154 and 153 independent of the springs 144 and 145 at the key K'. The said locking circuit extends from 40 ground G¹² through the contact of springs 103 and 102, springs 157 and 158, springs 153 and 154 and through the said relay S to battery B. A further result of the energization of relay S is to close a circuit 45 through the ringing relay U at the springs 151 and 152. The said ringing relay circuit extends from ground G¹¹ through interrupting device T contacts of springs 152 and 151, through winding of ringing relay U to the 50 battery B. The relay U, upon energizing, disconnects the calling line from the called line and bridges the generator R' across the called line over the following path: from one terminal of the said generator, springs 55 148 and 142 of key k', springs 159 and 160, tip of plug P, tip spring 125 of jack J', to and through the substation A', springs 132 and 131, ring spring 126 of jack J', ring of plug P, springs 163 and 162 of relay U, coil 60 V and springs 146 and 147 back to the opposite terminal of generator R'. The ringing relay U is energized intermittently, through the medium of interrupter T. The springs 160 and 161 and springs 163 and 164 of relay 65 U are shunted by a very high resistance or by a very small condenser. This allows a very small portion of the ringing current to be transmitted back through the calling line to the calling substation, thus giving the calling subscriber an audible ringing signal, 70 informing him that the called subscriber is being signaled. I have found that the high resistance may be merely a line drawn by a carbon pencil on the insulating mounting between the said springs or the condenser may 75 be the capacity effect of a pair of insulated wires twisted together one wire electrically connected to one spring and the other to the other spring. Either method gives very satisfactory results. Upon the response of 80 the called subscriber his line is provided with talking current through the windings 170 and 171 of the relay Y which is normally bridged across the conductors 137 and 138. The relay Y, upon energizing, opens 85 the circuit of the supervisory lamp t² at the springs 155 and 156 and opens the circuit of the relay S at the springs 157 and 158. The relay S, upon deenergizing, opens the circuit of relay U at the springs 151 and 152. 90 The subscribers may now carry on an uninterrupted conversation over the heavy conductors shown.

The replacing of the receiver at the called and calling substations signifies to the operator that the conversation has terminated. When the receiver at the substation A is restored to the switch hook, the separation of the hook switch springs 7 and 8 destroys the energizing circuit of the line relay F. The 95 relay F, upon deenergizing, causes the supervisory lamp t to glow over the following circuit: from ground G¹² through the springs 103 and 102, springs 73 and 72 and the lamp t to battery B. The replacing of 100 the receiver at the called substation A' opens the circuit of the relay Y, which, upon deenergizing, closes a circuit through the supervisory lamp t². This circuit extends from ground G¹² through the springs 103 and 102, springs 155 and 156 and the said lamp t² to battery B. The operator receiving the disconnect signal removes the plug P from the jack J', thus breaking the circuit of the relay Q and the cut-off winding 133 of line 110 switch C'. The relay Q, upon deenergizing, opens the circuit of the relay W at the springs 102 and 103, removes the ground from the holding winding 15 of line switch C at springs 98 and 99, and opens the circuit 115 of the supervisory lamps t and t². The holding winding of the line switch C, upon deenergizing, allows the line switch plunger to be returned to normal. The relay W is preferably made slow-acting, so that the line 120 switch C is given sufficient time to return to normal before the release conductor 79 is again connected to the group busying relay 125 common to the various other cord circuits.

It will, therefore, be seen that I provide a 130

semi-automatic traffic distributor system, in which an operator may be assigned exclusively to take care of the traffic over a certain number of trunks. Another operator 5 may be assigned to take care of traffic over another group of trunks, and so on. There may be a plurality of groups of subscribers' lines and from each group of lines trunks may run to each operator. For example, in 10 a system in which the so-called Keith units are used, one or more trunks from each unit may be assigned to each operator. Furthermore, it will be seen that I provide means for insuring that no two subscribers will call 15 in on an operator at the same time. When a subscriber calls in on one trunk he energizes the magnet I. This magnet energizes regardless of which trunk is taken. When a subscriber takes a trunk he makes, of course, 20 his own particular trunk busy and by energizing the magnet I he makes all the remaining trunks which are at the time unseized busy until the operator completes the connection. I do not claim broadly this 25 idea in this case, but I do claim the use of the busy trunk or of the release trunk for making the said non-seized trunks busy.

It will be seen furthermore that even if 30 two subscribers were to take off their receivers at the same instant and were to take trunks simultaneously, the relay N nearest the ground G^{13} would cut off the ground G^{13} from all of the relays O associated with 35 those trunks which are farther from ground G^{13} , and this makes it impossible for one of the subscribers to cut in on the operator's head-set. Obviously, therefore, the provision of the relay I and of the relays N make it absolutely certain that no two subscribers 40 may cut in on the operator's position at the same time.

It will be seen, therefore, that by the provision of the slow-acting relay W it is impossible for any subscriber who is initiating 45 a call and who is holding the relay I energized to interfere with the release of some other subscriber who is through talking, because the relay W prevents the relay I from putting a guarding potential on the trunk 50 release conductor until after the connection is restored. In this system it will be seen that I have also provided means for disconnecting a trunk automatically from an auxiliary circuit, such as the operator's head- 55 set, as soon as the operator extends the connection. Furthermore, the act of the operator extending the connection beyond her position automatically restores the circuit and makes it possible for any relay O to be 60 energized in a new connection.

I have also provided a new arrangement by means of which the relays Z' and Z^3 operate to give a single kick to the operator when she tests a called line, if the called line is 65 not the same one that originated the call.

On the other hand, if it is the one that originated the call, the action of the relay Z' is kept up and impulses continue to be repeated to the operator, which indicate to her that the connection is from one party line 70 subscriber to another one on the same line. The relay Z' will continue to flutter in this last instance, because through the action of the springs 174 and 175 it short circuits itself to ground via the springs 115 and 116 of 75 relay O, which is the ground on the release conductor 79, which is holding up the line switch C. It will be seen in this connection that I provide also a supervisory relay Y and that this relay is normally connected 80 with the plug, whereas the relay Z' is normally disconnected from the plug. It will also be seen that I provide a new arrangement for automatically controlling the ringing current through the medium of the 85 starter relay S in combination with the keys, which starter relay S is provided with a locking circuit under the control of the relay Y. It will also be seen that I provide a new arrangement by means of which the ringer 90 relay U not only rings the called subscriber, but also notifies the calling subscriber that ringing current is being supplied to the called line. Also I provide a new arrangement by means of which the relays Q and 95 Q directly control the operation of the meter magnet.

What I claim as my invention is:—

1. In a telephone system, a plurality of trunks each comprising a main circuit and a busy test circuit, means including a plurality of progressively movable trunking switches controlled by a common master switch mechanism, for seizing any one of said trunks and means operable when a 100 trunk is seized for making every other idle trunk busy when the seizure is made, means for releasing the connection comprising a release circuit associated with each trunk, and means for opening the release circuit to initiate the release, said busy test and release circuits having sections in common.

2. In a telephone system, a plurality of trunks each comprising a main circuit and a busy test circuit, means for seizing any 110 one of said trunks and means operable when a trunk is seized for making every other idle trunk busy when the seizure is made, means for releasing the connection comprising a release circuit associated with each trunk 115 closed during conversation, means for opening the release circuit to initiate the release, said busy test and release circuits having sections in common, and means for extending the main circuit and for rendering the 120 said other trunks non-busy when the circuit is extended.

3. In a telephone system, a plurality of trunks each comprising a main circuit and a busy test circuit, means including a plu- 130

- rality of progressively movable trunking switches controlled by a common master switch mechanism for seizing any one of said trunks, means for releasing the connection comprising a release circuit, means for opening said release circuit to initiate the release, said busy test circuit and release circuit having sections in common; another group of trunks each comprising a main circuit and a busy test circuit, means for seizing any one of the trunks of the second group, and means operable when a trunk is seized for making every other trunk in both groups busy if idle when the said seizure is made.
4. In a telephone system, a plurality of trunks each comprising a main circuit and a busy test circuit, means including a plurality of progressively movable trunking switches controlled by a common master switch mechanism for seizing any one of said trunks, means for releasing the connection comprising a release circuit, said busy test circuit and release circuit having sections in common; another group of trunks each comprising a main circuit and a busy test circuit, means for seizing any one of the trunks of the second group, means for releasing the connection comprising a release circuit, means for opening said release circuit to initiate the release, said last busy test circuit and said last release circuit having sections in common, and means operable when a trunk is seized for making every other trunk in both groups busy if idle when the said seizure is made.
5. In a telephone system, a plurality of trunks each comprising a main circuit and a busy test circuit, means including a plurality of progressively movable trunking switches controlled by a common master switch mechanism for seizing any one of said trunks, means for releasing the connection comprising a release circuit, means for opening said release circuit to initiate the release, said busy test circuit and release circuit having sections in common; another group of trunks each comprising a main circuit and a busy test circuit, means for seizing any one of the trunks of the second group, means for releasing the connection comprising a release circuit, said busy test circuit and release circuit having sections in common; another group of trunks each comprising a main circuit and a busy test circuit, means for seizing any one of the trunks of the second group, means operable when a trunk is seized for making every other trunk in both groups busy if idle when the said seizure is made, and means for extending the main circuit and for rendering the said other trunks non-busy when the circuit is extended.
6. In a telephone system, a plurality of trunks each comprising a main circuit and a busy test circuit, means for seizing any one of said trunks, means for releasing the connection comprising a release circuit, said busy test circuit and release circuit having sections in common; another group of trunks each comprising a main circuit and a busy test circuit, means for seizing any one of the trunks of the second group, means for releasing the connection comprising a release circuit, said busy test circuit and release circuit having sections in common; another group of trunks each comprising a main circuit and a busy test circuit, means for seizing any one of the trunks of the second group, means operable when a trunk is seized for making every other trunk in both groups busy if idle when the said seizure is made, and means for extending the main circuit and for rendering the said other trunks non-busy when the circuit is extended.
7. In a telephone system, a plurality of trunks each comprising a talking circuit and a release conductor associated therewith, means for establishing connection with any one of said trunks, release apparatus for breaking the connection, a release circuit closed during conversation comprising the release conductor associated with the connected trunk for controlling said release apparatus, means for opening said release circuit to initiate the release, means for making any trunk busy when seized comprising the release conductor, and means operable when any trunk is seized for making every other trunk, idle at the time of seizure, busy via its release conductor when the seizure is made.
8. In a telephone system, a plurality of trunks each comprising a talking circuit and a release conductor associated therewith, means for establishing connection with any one of said trunks, release apparatus for breaking the connection, a release circuit closed during conversation comprising the release conductor associated with the connected trunk for controlling said release apparatus, means for opening said release circuit to initiate the release, means for making any trunk busy when seized comprising the release conductor; another group of trunks each comprising a main talking circuit, means for establishing connection with any one of the trunks of said second group, release apparatus for breaking said connection in the second group, a release circuit comprising a conductor associated with the connected trunk and means for making any trunk of the second group busy when seized comprising its release conductor, and means operable when any trunk is seized for making every other trunk in both groups, idle at the time of seizure, busy via its release conductor when the seizure is made.
9. In a telephone system, a plurality of trunks each comprising a talking circuit and a release conductor associated therewith, means for establishing connection with any one of said trunks, release apparatus for breaking the connection, a release circuit closed during conversation comprising the release conductor associated with the connected trunk for controlling said release apparatus, means for opening said release circuit to initiate the release, means for making any trunk busy when seized comprising the release conductor; another group of trunks each comprising a main talking circuit, means for establishing connection with any one of the trunks of said second group, release apparatus for breaking said connection in the second group, a release circuit comprising a conductor associated with the connected trunk and means for making any trunk of the second group busy when seized comprising its release conductor, and means operable when any trunk is seized for making every other trunk in both groups, idle at the time of seizure, busy via its release conductor when the seizure is made.

- cuit to initiate the release, means for making any trunk busy when seized comprising the release conductor, means operable when any trunk is seized for making every other trunk, 5 idle at the time of seizure, busy via its release conductor when the seizure is made, and means for extending the main circuit and for rendering the said other trunks non-busy when the circuit is extended.
- 10 10. In a telephone system, a plurality of trunks each comprising a talking circuit and a release conductor associated therewith, means for establishing connection with any one of said trunks, release apparatus for 15 breaking the connection, a release circuit closed during conversation comprising the release conductor associated with the connected trunk for controlling said release apparatus, means for opening said release circuit to initiate the release, means for making any trunk busy when seized comprising the release conductor; another group of trunks each comprising a main talking circuit, means for establishing connection with any 20 one of the trunks of said second group, release apparatus for breaking said connection in the second group, a release circuit comprising a conductor associated with the connected trunk and means for making any 25 30 trunk of the second group busy when seized comprising its release conductor, means operable when any trunk is seized for making every other trunk in both groups, idle at the time of seizure, busy via its release conductor when the seizure is made, and means for extending the main circuit and for rendering the said other trunks non-busy when the circuit is extended.
11. In a telephone system, a plurality of 40 trunks each comprising a main circuit and a busy test circuit, means including a plurality of progressively movable trunking switches controlled by a common master switch mechanism for seizing any one of 45 said trunks and electromagnetic means operable when a trunk is seized for making every other idle trunk busy when the seizure is made, and means for releasing the connection comprising a release circuit associated 50 with each trunk, means for opening said release circuit to initiate the release, said busy test and release circuits having sections in common.
12. In a telephone system, a plurality of 55 trunks each comprising a main circuit and a busy test circuit, means including a plurality of progressively movable trunking switches controlled by a common master switch mechanism for seizing any one of 60 said trunks and electromagnetic means operable when a trunk is seized for making every other idle trunk busy when the seizure is made, means for releasing the connection comprising a release circuit associated with 65 each trunk, means for opening said release circuit to initiate the release, said busy test and release circuits having sections in common, and means for extending the main circuit and for rendering the said other trunks non-busy when the circuit is extended.
13. In a telephone system, a plurality of trunks each comprising a main circuit and a busy test circuit, means for seizing any one of said trunks, means for releasing the connection comprising a release circuit closed during conversation, means for opening said release circuit to initiate the release, said busy test circuit and release circuit having sections in common; another group of trunks each comprising a main circuit and a busy test circuit, means for seizing any one of the trunks of the second group, and electromagnetic means operable when a trunk is seized for making every other trunk in both groups busy if idle when the said seizure is made.
14. In a telephone system, a plurality of trunks each comprising a main circuit and a busy test circuit, means for releasing any one of said trunks, means for releasing the connection comprising a release circuit, said busy test circuit and release circuit having sections in common; another group of trunks each comprising a main circuit and a busy test circuit, means for seizing any one of the trunks of the second group, means for releasing the connection comprising a release circuit closed during conversation, means for opening said release circuit to initiate the release, said last busy test circuit and said last release circuit having sections in common, and electromagnetic means operable when a trunk is seized for making every other trunk in both groups busy if idle when the said seizure is made.
15. In a telephone system, a plurality of trunks each comprising a main circuit and a busy test circuit, means including a plurality of progressively movable trunking switches controlled by a common master switch mechanism for seizing any one of said trunks, means for releasing the connection comprising a release circuit, means for opening said release circuit to initiate the release, said busy test circuit and release circuit having sections in common; another group of trunks each comprising a main circuit and a busy test circuit, means for seizing any one of the trunks of the second group, electromagnetic means operable when a trunk is seized for making every other trunk in both groups busy if idle when the said seizure is made, and means for extending the main circuit and for rendering the said other trunks non-busy when the circuit is extended.
16. In a telephone system, a plurality of trunks each comprising a main circuit and a busy test circuit, means including a plurality of progressively movable trunking switches controlled by a common master switch mechanism for seizing any one of said trunks, means for releasing the connection comprising a release circuit, means for opening said release circuit to initiate the release, said busy test circuit and release circuit having sections in common; another group of trunks each comprising a main circuit and a busy test circuit, means for seizing any one of the trunks of the second group, electromagnetic means operable when a trunk is seized for making every other trunk in both groups busy if idle when the said seizure is made, and means for extending the main circuit and for rendering the said other trunks non-busy when the circuit is extended.

switches controlled by a common master switch mechanism for seizing any one of said trunks, means for releasing the connection comprising a release circuit, said busy test circuit and release circuit having sections in common; another group of trunks each comprising a main circuit and a busy test circuit, means for seizing any one of the trunks of the second group, means for releasing the connection comprising a release circuit, means for opening said release circuit to initiate the release, said last busy test circuit and said last release circuit having sections in common, electromagnetic means operable when a trunk is seized for making every other trunk in both groups busy if idle when the said seizure is made, and means for extending the main circuit and for rendering the said other trunks non-busy when the circuit is extended.

17. In a telephone system, a plurality of trunks each comprising a talking circuit and a release conductor associated therewith, means for establishing connection with any one of said trunks, release apparatus for breaking the connection, a release circuit closed during conversation comprising the release conductor associated with the connected trunk for controlling said release apparatus, means for opening said release circuit to initiate the release, means for making any trunk busy when seized comprising the release conductor, and electromagnetic means operable when any trunk is seized for making every other trunk, idle at the time of seizure, busy via its release conductor when the seizure is made.

18. In a telephone system, a plurality of trunks each comprising a talking circuit and a release conductor associated therewith, means for establishing connection with any one of said trunks, release apparatus for breaking the connection, a release circuit closed during conversation comprising the release conductor associated with the connected trunk for controlling said release apparatus, means for opening said release circuit to initiate the release, means for making any trunk busy when seized comprising the release conductor; another group of trunks each comprising a main talking circuit, means for establishing connection with any one of the trunks of said second group, release apparatus for breaking said connection in the second group, a release circuit comprising a conductor associated with the connected trunk and means for making any trunk of the second group busy when seized comprising its release conductor, and electromagnetic means operable when any trunk is seized for making every other trunk in both groups, idle at the time of seizure, busy via its release conductor when the seizure is made.

19. In a telephone system, a plurality of

trunks each comprising a talking circuit, and a release conductor associated therewith, means for establishing connection with any one of said trunks, release apparatus for breaking the connection, a release circuit closed during conversation comprising the release conductor associated with the connected trunk for controlling said release apparatus, means for opening said release circuit to initiate the release, means for making any trunk busy when seized comprising the release conductor, electromagnetic means operable when any trunk is seized for making every other trunk, idle at the time of seizure, busy via its release conductor when the seizure is made, and means for extending the main circuit and for rendering the said other trunks non-busy when the circuit is extended.

20. In a telephone system, a plurality of trunks each comprising a talking circuit and a release conductor associated therewith, means for establishing connection with any one of said trunks, release apparatus for breaking the connection, a release circuit closed during conversation comprising the release conductor associated with the connected trunk for controlling said release apparatus, means for opening said release circuit to initiate the release, means for making any trunk busy when seized comprising the release conductor; another group of trunks each comprising a main talking circuit, means for establishing connection with any one of the trunks of said second group, release apparatus for breaking said connection in the second group, a release circuit comprising a conductor associated with the connected trunk and means for making any trunk of the second group busy when seized comprising its release conductor, electromagnetic means operable when any trunk is seized for making every other trunk in both groups, idle at the time of seizure, busy via its release conductor when the seizure is made, and means for extending the main circuit and for rendering said other trunks non-busy when the circuit is extended.

21. In a telephone system, a plurality of trunks each comprising a main circuit and a busy test circuit, means including a plurality of progressively movable trunking switches controlled by a common master switch mechanism for seizing any one of said trunks and for making the seized trunk busy, means operable when a trunk is seized for making every other trunk busy, when the seizure is made, via their busy test circuits, means for releasing the seized trunk comprising a release circuit passing over the busy test circuit, and means for opening said release circuit to initiate the release.

22. In a telephone system, a plurality of lines, a common battery, means for sending current from said battery over said lines,

a plurality of trunks each comprising a main circuit and a busy test circuit, means including a plurality of progressively movable trunking switches controlled by a common master switch mechanism for seizing any one of said trunks for one of said lines to form an extended talking circuit of the calling line and the said main circuit, means for making said seized trunk busy, means operable when a trunk is seized for making every other trunk busy as a result, via their busy test circuits, all as a result of the first establishment of current in the calling line, means for releasing the seized trunk comprising a release circuit passing over the busy test circuit, and means for opening said release circuit to initiate the release.

23. In a telephone system, a plurality of trunks each comprising a main circuit and a busy test circuit, automatic means including a plurality of progressively movable trunking switches controlled by a common master switch mechanism for seizing any one of said trunks and for making the seized trunk busy, automatic means operable when a trunk is seized for making every other trunk busy, when the seizure is made, via their busy test circuits, automatic means for releasing the seized trunk comprising a release circuit passing over the busy test circuit, and means for opening said release circuit to initiate the release.

24. In a telephone system, a plurality of lines, a common battery, means for sending current from said battery over said lines, a plurality of trunks each comprising a main circuit and a busy test circuit, automatic means for seizing any one of said trunks for one of said lines to form an extended talking circuit of the calling line and the said main circuit, automatic means for making said seized trunk busy, means operable when a trunk is seized for making every other trunk busy as a result, via their busy test circuits, all as a result of the first establishment of current in the calling line, automatic means for releasing the seized trunk comprising a release circuit closed during conversation passing over the busy test circuit, and means for opening said release circuit to initiate the release.

25. In a telephone system, a plurality of trunks each comprising a main circuit and a busy test circuit, means including a plurality of progressively movable trunking switches controlled by a common master switch mechanism for seizing any one of said trunks and for making the seized trunk busy; another group of trunks each comprising a main circuit and a busy test circuit, means for seizing any one of the trunks in said second group and for making the trunk busy when seized; means operable when a trunk is seized for making every other trunk in either group busy when a seizure is made via their busy test circuits, and means for opening their busy

test circuits, means for releasing the seized trunk comprising a release circuit passing over the busy test circuit, and means for opening said release circuit to initiate the release.

26. In a telephone system, a plurality of trunks each comprising a main circuit and a busy test circuit, means including a plurality of progressively movable trunking switches controlled by a common master switch mechanism for seizing any one of said trunks and for making the seized trunk busy; another group of trunks each comprising a main circuit and a busy test circuit, means for seizing any one of the trunks in said second group and for making the trunk busy when seized; means operable when a trunk is seized for making every other trunk in either group busy when a seizure is made via their busy test circuits, means for releasing the seized trunk comprising a release circuit passing over the busy test circuit, means for opening said release circuit to initiate the release, and means for extending the main circuit and for rendering the said other trunks non-busy when the circuit is extended.

27. In a telephone system, a plurality of trunks each comprising a main circuit and a busy test circuit, automatic means including a plurality of progressively movable trunking switches controlled by a common master switch mechanism for seizing any one of said trunks and for making the seized trunk busy; another group of trunks each comprising a main circuit and a busy test circuit, automatic means for seizing any one of the trunks in said second group and for making the trunk busy when seized; automatic means operable when a trunk is seized for making every other trunk in either group busy when a seizure is made via their busy test circuits, automatic means for releasing the seized trunk comprising a release circuit passing over the busy test circuits, and means for opening said release circuit to initiate the release.

28. In a telephone system, a plurality of trunks each comprising a main circuit and a busy test circuit, an auxiliary circuit and connecting means for each trunk for connecting the trunk with the auxiliary circuit, means for seizing any one of said trunks and for making the seized trunk busy, means operable when a trunk is seized for making every other idle trunk busy as a result of the seizure, means for operating the said connecting means of the seized trunk to connect the seized trunk to the auxiliary circuit, and means for making the connecting means of the other trunks inoperative.

29. In a telephone system, a plurality of trunks each comprising a main circuit and a busy test circuit, an auxiliary circuit and connecting means for each trunk for con-

- necting the trunk with the auxiliary circuit, means for seizing any one of said trunks and for making the seized trunk busy, means operable when a trunk is seized for making 5 every other idle trunk busy as a result of the seizure, means for operating the said connecting means of the seized trunk to connect the seized trunk to the auxiliary circuit, means for making the connecting means of 10 the other trunks inoperative, and means for releasing the seized trunk comprising a release circuit passing over the busy test circuit.
30. In a telephone system, a plurality of 15 trunks each comprising a main circuit and a busy test circuit, an auxiliary circuit and connecting means for each trunk for connecting the trunk with the auxiliary circuit, means for seizing any one of said trunks 20 and for making the seized trunk busy, means operable when a trunk is seized for making every other idle trunk busy as a result of the seizure, means for operating the said connecting means of the seized trunk to connect 25 the seized trunk to the auxiliary circuit, means for making the connecting means of the other trunks inoperative, and means for extending the main circuit and for rendering the said other trunks non-busy when the 30 circuit is extended.
31. In a telephone system, a plurality of 35 trunks each comprising a main circuit and a busy test circuit, an auxiliary circuit and connecting means for each trunk for connecting the trunk with the auxiliary circuit, means for seizing any one of said trunks and for making the seized trunk busy, means operable when a trunk is seized for making 40 every other idle trunk busy as a result of the seizure, means for operating the said connecting means of the seized trunk to connect the seized trunk to the auxiliary circuit, means for making the connecting means of 45 the other trunks inoperative, means for releasing the seized trunk comprising a release circuit passing over the busy test circuit, and means for extending the main circuit and for rendering the said other trunks non-busy when the circuit is extended.
50. 32. In a telephone system, a plurality of 55 trunks, means for seizing any one of said trunks, means for extending a connection from the seized trunk to an operator's head set, and means controlled from the seized 60 trunk for preventing the maintenance of an extension from another one of said trunks to said operator's head set, said last means also controlled from the seized trunk to automatically extend a connection from the other trunk.
33. In a telephone system, a plurality of 65 trunks, means for seizing any one of said trunks, means for extending a connection from the seized trunk to an operator's head set, and means controlled from the seized
- trunk for rendering inoperative the said second means associated with another trunk, said last means also controlled from the seized trunk to automatically extend a connection from the other trunk. 70
34. In a telephone system, a plurality of trunks, means for seizing any one of said trunks, means for extending a connection from the seized trunk to an operator's head set, and electromagnetic means controlled 75 from the seized trunk for preventing the maintenance of an extension from another one of said trunks to said operator's head set, said last means also controlled from the seized trunk to automatically extend a connection from the other trunk. 80
35. In a telephone system, a plurality of trunks, means for seizing any one of said trunks, means for extending a connection from the seized trunk to an operator's head 85 set, and electromagnetic means controlled from the seized trunk for rendering inoperative the said second means associated with another trunk, said last means also controlled from the seized trunk to automatically extend a connection from the other trunk. 90
36. In a telephone system, a plurality of trunks, means for seizing any one of said trunks, means for extending a connection 95 from the seized trunk to an operator's head set, and means controlled from the seized trunk for rendering inoperative the said second means of another trunk to prevent two connections existing at the same time from 100 two separate trunks to the operator's head set, said last means also controlled from the seized trunk to automatically extend a connection from the other trunk.
37. In a telephone system, a plurality of 105 trunks, means for seizing any one of said trunks, means for extending a connection from the seized trunk to an operator's head set, means controlled from the seized trunk for rendering inoperative the said second 110 means of another trunk to prevent two connections existing at the same time from two separate trunks to the operator's head set, and means under the control of the operator for extending connection from the seized trunk and for then restoring said second means to operative condition, said last means also controlled from the seized trunk to automatically extend a connection from the other trunk. 115
38. In a telephone system, a plurality of 120 trunks, automatic means for seizing any one of said trunks, means for extending a connection from the seized trunk to an operator's head set, and means controlled from the seized trunk for rendering inoperative the 125 said second means of another trunk to prevent two connections existing at the same time from two separate trunks to the operator's head set, said last means also controlled from the seized trunk to automatically extend a connection from the other trunk. 130

trolled from the seized trunk to automatically extend a connection from the other trunk.

39. In a telephone system, a plurality of 5 trunks, means for seizing any one of said trunks, means for extending a connection from the seized trunks to an operator's head set, and automatic means controlled from the seized trunk for rendering inoperative 10 the said second means of another trunk to prevent two connections existing at the same time from two separate trunks to the operator's head set, said last means also controlled from the seized trunk to automatically 15 extend a connection from the other trunk.

40. In a telephone system, a plurality of trunks, automatic means for seizing any one of said trunks, means for extending a connection 20 from the seized trunk to an operator's head set, and automatic means controlled from the seized trunk for rendering inoperative the said second means of another trunk to prevent two connections existing 25 at the same time from two separate trunks to the operator's head set, said last means also controlled from the seized trunk to automatically extend a connection from the other trunk.

41. In a telephone system, a plurality of trunks, automatic means for seizing any one of said trunks, means for extending a connection from the seized trunk to an operator's head set, means controlled from the 35 seized trunk for rendering inoperative the said second means of another trunk to prevent two connections existing at the same time from two separate trunks to the operator's head set, and means under the control 40 of the operator for extending connection from the seized trunk and for then restoring said second means to operative condition, said last means also controlled from the seized trunk to automatically extend a 45 connection from the other trunk.

42. In a telephone system, a plurality of trunks, means for seizing any one of said trunks, means for extending a connection from the seized trunk to an operator's head 50 set, automatic means controlled from the seized trunk for rendering inoperative the said second means of another trunk to prevent two connections existing at the same time from two separate trunks to the operator's head set, and means under the control 55 of the operator for extending connection from the seized trunk and for then restoring said second means to operative condition, said last means also controlled 60 from the seized trunk to automatically extend a connection from the other trunk.

43. In a telephone system, a plurality of trunks, automatic means for seizing any one of said trunks, means for extending a connection 65 from the seized trunks to an op-

erator's head set, automatic means controlled from the seized trunk for rendering inoperative the said second means of another trunk to prevent two connections existing at the same time from two separate 70 trunks to the operator's head set, and means under the control of the operator for extending connection from the seized trunk and for then restoring said second means to operative condition, said last means also 75 controlled from the seized trunk to automatically extend a connection from the other trunk.

44. In a telephone system, a line, a trunk normally disconnected from said line, an operator's head set normally disconnected from said trunk, a progressively movable switch for establishing connection with said trunk line, and a non-progressively movable switch for then connecting said trunk line with said operator's head set, said last means also controlled from the seized trunk to automatically extend a connection from the other trunk.

45. In a telephone system, a plurality of 90 lines, a common battery, means for sending current from said battery over said lines, a plurality of trunks accessible to said lines, an operator's head set and an operator's position, means for connecting a trunk with 95 the operator's head set and means for connecting another trunk with the operator's head set, means for connecting one of said lines with one of said trunks whereby it may then be connected with said operator's head 100 set responsive to the first establishment of current in the calling line, and means for rendering the other head set connecting means inoperative, lines extending from the operator's position, and operator controlled 105 means for extending connection from the calling line to one of said last named lines and for then rendering operative the said means previously rendered inoperative, said last means also controlled from the seized 110 trunk to automatically extend a connection from the other trunk.

46. In a telephone system, a plurality of trunks, automatic means for seizing any one of said trunks, means for extending a connection from the seized trunk to an operator's head set, and automatic means controlled from the seized trunk for preventing the maintenance of an extension from another one of said trunks to said operator's 115 head set, said last means also controlled from the seized trunk to automatically extend a connection from the other trunk.

47. In a telephone system, a plurality of trunks, automatic means for seizing any one 120 of said trunks, means for extending a connection from the seized trunk to an operator's head set, and automatic means controlled from the seized trunk for rendering inoperative the said second means associ- 125

ated with another trunk, said last means also controlled from the seized trunk to automatically extend a connection from the other trunk.

5 48. In a telephone system, a plurality of trunks each comprising a main circuit and a busy test circuit, means for seizing any one of said trunks and for making the seized trunk busy, means operable when a trunk is seized for applying a busy potential to every other idle trunk via their busy test circuits to make the idle trunks busy, means for preventing the said last potential applying means from applying a potential to the busy test circuit of any trunk that is busy at the time of said seizure, and means for releasing said last mentioned busy trunk comprising release circuits passing over the busy test circuits of said last busy trunks.

10 49. In a telephone system, a plurality of trunks each comprising a main circuit and a busy test circuit, means for seizing any one of said trunks and for making the seized trunk busy, means operable when a trunk is seized for applying a busy potential to every other idle trunk via their busy test circuits to make the idle trunks busy, means for preventing the said last potential applying means from applying a potential to the busy test circuit of any trunk that is busy at the time of said seizure, means for releasing said last mentioned busy trunks comprising release circuits passing over the busy test circuits of said last busy trunks and means for extending the main circuit and for rendering the said other trunks non-busy when the circuit is extended.

15

20

25

30

35

50. In a telephone system, a plurality of trunks each comprising a main circuit and a busy test circuit, automatic means for seizing any one of said trunks and for making the seized trunk busy, automatic means operable when a trunk is seized for applying a busy potential to every other idle trunk via their busy test circuits to make the idle trunks busy, automatic means for preventing the said last potential applying means from applying a potential to the busy test circuit of any trunk that is busy at the time of said seizure, and means for releasing the seized trunk and other busy trunk comprising release circuits passing over the busy test circuits of the seized trunks.

51. In a telephone system, a plurality of
55 trunks each comprising a main circuit and a
busy test circuit, automatic means for seiz-
ing any one of said trunks and for making
the seized trunk busy, automatic means op-
erable when a trunk is seized for applying
60 a busy potential to every other idle trunk
via their busy test circuits to make the idle
trunks busy, automatic means for preventing
the said last potential applying means from
applying a potential to the busy test circuit
65 of any trunk that is busy at the time of said

seizure, automatic means for releasing said last mentioned busy trunks comprising release circuits passing over the busy test circuits of said last busy trunk and manual means for extending the main circuit and for rendering the said other now busy trunks non-busy when the circuit is extended. 70

52. In a telephone system, a plurality of trunks each comprising a main circuit and a busy test circuit, an auxiliary circuit and connecting means for each trunk for connecting the trunk with the auxiliary circuit, automatic means for seizing any one of said trunks and for making the seized trunk busy, automatic means operable when a trunk is seized for making every other idle trunk busy as a result of the seizure, automatic means for operating the said connecting means of the seized trunk to connect the seized trunk to the auxiliary circuit, automatic means for making the connecting means of the other trunks inoperative, and automatic means for releasing the seized trunk comprising a release circuit passing over the busy test circuit. 75 80 85 90

53. In a telephone system, a plurality of trunks each comprising a main circuit and a busy test circuit, an auxiliary circuit and connecting means for each trunk for connecting the trunk with the auxiliary circuit, 95 automatic means for seizing any one of said trunks and for making the seized trunk busy, automatic means operable when a trunk is seized for making every other idle trunk busy as a result of the seizure, automatic means for operating the said connecting means of the seized trunk to connect the seized trunk to the auxiliary circuit, automatic means for making the connecting means of the other trunks inoperative, and manual means for extending the main circuit and for rendering the said other trunks non-busy when the circuit is extended. 100 105

54. In a telephone system, a plurality of trunks each comprising a main circuit and a busy test circuit, an auxiliary circuit and connecting means for each trunk for connecting the trunk with the auxiliary circuit, automatic means for seizing any one of said trunks and for making the seized trunk busy, automatic means operable when a trunk is seized for making every other idle trunk busy as a result of the seizure, automatic means for operating the said connecting means of the seized trunk to connect the seized trunk to the auxiliary circuit, automatic means for making the connecting means of the other trunks inoperative, automatic means for releasing the seized trunk comprising a release circuit passing over the busy test circuit, and manual means for extending the main circuit and for rendering the first said idle trunks non-busy when the circuit is extended. 110 115 120 125

55. In a telephone system, a plurality of 130

- busy test circuits to make the idle trunks busy, automatic means for releasing the seized trunk comprising a release circuit passing over the busy test circuit, slow-acting means for preventing the said last potential applying means from applying a potential to the busy test circuits of any other trunk that is busy at the time of said seizure whereby interference with the release is prevented, and manual means for extending the main circuit before the release and for rendering the first said idle trunks non-busy when the extension is made.
63. In a telephone system, a plurality of trunks, means for seizing any one of said trunks, means for extending a connection from the seized trunk, means controlled from the seized trunk for rendering inoperative the said second means associated with another trunk, means for again extending connection from the seized trunk and for then restoring the means rendered inoperative to operative condition, said third means also controlled from the seized trunk to automatically extend a connection from the other trunk.
64. In a telephone system, a plurality of trunks, means for seizing any one of said trunks, means for extending a connection from the seized trunk, means controlled from the seized trunk for preventing the maintenance of an extension from another one of said trunks, and means for again extending connection from the seized trunk and for then restoring the third means to operative condition and for controlling said third means from the seized trunk to automatically extend a connection from the other trunk.
65. In a telephone system, a plurality of lines, a common battery, means for sending current from said battery over said lines, a plurality of trunks, an operator's head set and an operator's position, a line extending beyond the operator's position, automatic means including a plurality of progressively movable trunking switches controlled by a common master switch mechanism for extending connection from one of said first lines when a subscriber calls to a trunk line and from the trunk line to the operator's head set responsive to the first establishment of current in the calling subscriber's line, and means for making said operator's head set inaccessible to the remaining trunk lines; operator controlled means for extending connection from the connected trunk to the line beyond and for then automatically extending a connection from another trunk line to the operator's head set.
66. In a telephone system, a plurality of trunks each comprising a main circuit and a busy test circuit, means including a plurality of progressively movable trunking switches controlled by a common master switch mechanism for seizing any one of said trunks and for making the seized trunk busy, means operable when a trunk is seized for making every other trunk busy, when the seizure is made via their busy test circuits, means for extending the main circuit and for rendering said other trunks non-busy when the circuit is extended and means for releasing the seized trunk comprising a release circuit passing over the busy test circuit.
67. In a telephone system, a plurality of lines, a common battery, means for sending current from said battery over said lines, a plurality of trunks each comprising a main circuit and a busy test circuit, means including a plurality of progressively movable trunking switches controlled by a common master switch mechanism for seizing any one of said trunks for one of said lines to form an extended talking circuit of the calling line and the said main circuit, means for making said seized trunk busy, means operable when a trunk is seized for making every other trunk busy as a result, via their busy test circuits, all as a result of the first establishment of current in the calling line, means for extending the main circuit and for rendering the said other trunks non-busy when the circuit is extended and means for releasing the seized trunk comprising a release circuit passing over the busy test circuit.
68. In a telephone system, a plurality of trunks each comprising a main circuit and a busy test circuit, automatic means including a plurality of progressively movable trunking switches controlled by a common master switch mechanism for seizing any one of said trunks and for making the seized trunk busy, automatic means operable when a trunk is seized for making every other trunk busy when the seizure is made via their busy test circuits, manual means for extending the main circuit, automatic means for rendering said other trunks non-busy when the circuit is extended and automatic means for releasing the seized trunk comprising a release circuit passing over the busy test circuit.
69. In a telephone system, a plurality of lines, a common battery, automatic means for sending current from said battery over said lines, a plurality of trunks each comprising a main circuit and a busy test circuit, automatic means including a plurality of progressively movable trunking switches controlled by a common master switch mechanism for seizing any one of said trunks for one of said lines to form an extended talking circuit of the calling line and the said main circuit, automatic means for making said seized trunk busy, automatic means operable when a trunk is seized for making every other trunk busy as a result, via their busy

test circuits, all as a result of the first establishment of current in the calling line, manual means for extending the main circuit, automatic means for rendering the said 5 other trunks non-busy when the circuit is extended and automatic means for releasing the seized trunk comprising a release circuit passing over the busy test circuit.

70. In a telephone system, a plurality of 10 trunks each comprising a main circuit and a busy test circuit, automatic means for seizing any one of said trunks and for making the seized trunk busy; another group of trunks each comprising a main circuit and a 15 busy test circuit, automatic means for seizing any one of the trunks in said second group and for making the trunk busy when seized; automatic means operable when a trunk is seized for making every other trunk 20 in either group busy when a seizure is made via their busy test circuits, manual means for extending the main circuit, automatic means for rendering the said other trunks non-busy when the circuit is extended and 25 automatic means for releasing the seized trunk comprising a release circuit closed during conversation passing over the busy test circuit.

71. In a telephone system, a plurality of 30 trunks each comprising a main circuit and a busy test circuit, an auxiliary circuit and connecting means for each trunk for connecting the trunk with the auxiliary circuit, means for seizing any one of said trunks 35 and for making the seized trunk busy, means operable when a trunk is seized for making every other idle trunk busy as a result of the seizure, means for operating the said connecting means of the seized trunk to connect 40 the seized trunk to the auxiliary circuit, means for making the connecting means of the other trunks inoperative, means for extending the main circuit, for rendering the other trunks non-busy when the circuit is extended, and for automatically disconnecting 45 from the auxiliary circuit.

72. In a telephone system, a plurality of trunks each comprising a main circuit and a 50 busy test circuit, an auxiliary circuit and connecting means for each trunk for connecting the trunk with the auxiliary circuit, means for seizing any one of said trunks and for making the seized trunk busy, means operable when a trunk is seized for making 55 every other idle trunk busy as a result of the seizure, means for operating the said connecting means of the seized trunk to connect the seized trunk to the auxiliary circuit, means for making the connecting 60 means of the other trunks inoperative, means for extending the main circuit, for rendering the other trunks non-busy when the circuit is extended, and for automatically disconnecting from the auxiliary circuit and

means for releasing the seized trunk comprising a release circuit passing over the 65 busy test circuit.

73. In a telephone system, a plurality of trunks each comprising a main circuit and a busy test circuit, an auxiliary circuit and 70 connecting means for each trunk for connecting the trunk with the auxiliary circuit, automatic means for seizing any one of said trunks and for making the seized trunk busy, automatic means operable when 75 a trunk is seized for making every other idle trunk busy as a result of the seizure, automatic means for operating the said connecting means of the seized trunk to connect the seized trunk to the auxiliary circuit, automatic means for making the connecting means of the other trunks inoperative, manual means for extending the main circuit, and automatic means for rendering the said other trunks non-busy and for automatically 80 disconnecting from the auxiliary circuit when the circuit is extended.

74. In a telephone system, a plurality of trunks each comprising a main circuit and a busy test circuit, an auxiliary circuit and 90 connecting means for each trunk for connecting the trunk with the auxiliary circuit, automatic means for seizing any one of said trunks and for making the seized trunk busy, automatic means operable when a 95 trunk is seized for making every other idle trunk busy as a result of the seizure, automatic means for operating the said connecting means of the seized trunk to connect the seized trunk to the auxiliary circuit, automatic means for making the connecting means of the other trunks inoperative, automatic means for releasing the seized trunk comprising a release circuit passing over the 100 busy test circuit, manual means for extending the main circuit, and automatic means for rendering the said other trunks non-busy and for automatically disconnecting from the auxiliary circuit when the circuit is extended.

75. In a telephone system, a plurality of trunks each comprising a main circuit and a busy test circuit, automatic means for seizing any one of said trunks and for making the seized trunk busy, automatic means operable when a trunk is seized for applying a busy potential to every other trunk via their busy test circuits to make the idle trunks busy, automatic means for releasing the seized trunk comprising a release circuit 115 passing over the busy test circuit, automatic means for preventing the said last potential applying means from applying a potential to the busy test circuits of any other trunk that is busy at the time of said seizure 120 whereby interference with the release is prevented, manual means for extending the main circuit, and automatic means for ren-

dering the said other trunks non-busy and for automatically disconnecting from the auxiliary circuit when the circuit is extended.

5 76. In a telephone system, a plurality of lines, a plurality of stations on some of said lines, means whereby one station may signal any other station comprising a cord circuit and a plurality of ringing generators associated with the said cord, a generator circuit, a key for each generator for connecting its generator with the generator circuit, a relay common to said keys and an energizing circuit for said relay whenever any key 10 is operated to connect a generator with the generator circuit, means controlled by said relay to connect the generator circuit with the talking circuit for signaling the called station, a locking circuit for said relay controlled by an auxiliary relay, a circuit for the auxiliary relay, means for closing said circuit to energize said auxiliary relay before the called subscriber answers when the 15 cord is connected with the called line, and means for breaking the said locking circuit when a called subscriber answers to cut off the ringing current.

77. A telephone exchange system comprising telephone lines, link circuits for interconnecting the lines, an operator's telephone set, a listening relay for each link circuit operating upon connection thereof with a telephone line to connect therewith the operator's telephone set, and a second relay 30 operated to disable all other listening relays while one of said listening relays is operated.

78. A telephone exchange system comprising telephone lines, link circuits for interconnecting the lines, an operator's telephone set, a switching device for each link circuit operating upon connection thereof with a 35

line to connect the operator's telephone set therewith, a switching mechanism operating to disable all other switching devices while 45

one switching device is actuated, and switching means operating upon connection of the link circuit in use with another line to restore the switching device thereof and the switching mechanism to normal position. 50

79. In a telephone exchange system; a plurality of subscribers' lines; a plurality of link circuits for interconnecting said lines; an operator's telephone set; first relays for each of said link circuits for including said operator's telephone set therewith when the answering end of a link circuit is connected with one of said subscribers' lines; a second relay for disconnecting said operator's telephone set from 55 said link circuit when the calling end of the link circuit is connected with another subscriber's line; and a third relay for preventing the operation of more than one of said first relays at the same time. 60

80. A telephone exchange system comprising telephone lines, link circuits for interconnecting the lines, an operator's telephone set, a listening relay for each link circuit operating upon connection thereof with a telephone line to connect the operator's telephone set therewith, a second relay operated to disable all other listening relays while one of said listening relays is operated, and electromagnetic mechanism operating upon 70 connection of the link circuit in use with another telephone line to release both the listening relay thereof and the second relay. 75

Signed by me at Chicago, Cook county, Illinois, this 12th day of November 1914.

TALBOT G. MARTIN.
